DESIGN FOR A WATER BATH

Alexander I. Newman, Chicago, Ill., assignor to Precision Scientific Company, Chicago, Ill., a corporation of Illinois

Application July 26, 1939, Serial No. 86,251

Term of patent 7 years

To all whom it may concern:

Be it known that I, Alexander I. Newman, a citizen of the United States, residing at Chicago, in the county of Cook and State of Illinois, have invented a new, original, and ornamental Design for a Water Bath, of which the following is a specification, reference being had to the accompanying drawing, forming part thereof.

Fig. 1 is a perspective view of a water bath embodying my new design.

Fig. 2 is a top plan view of the same, on a reduced scale.

Fig. 3 is a rear elevational view of the same, on a reduced scale.

I claim:

The ornamental design for a water bath, substantially as shown.
